UNITED STATES PATENT OFFICE.

GUSTAV EHRHARDT, OF EISENACH, GERMANY.

BREECH MECHANISM FOR GUNS.

SPECIFICATION forming part of Letters Patent No. 715,039, dated December 2, 1902.

Application filed June 13, 1902. Serial No. 111,525. (No model.)

To all whom it may concern:

Be it known that I, GUSTAV EHRHARDT, engineer, a citizen of the United States of America, residing at Eisenach, in the Grand Duchy of Saxe-Weimar and German Empire, have invented certain new and useful Improvements in or Relating to Breech Mechanism for Guns, of which the following is a specification.

10 My invention relates to breech mechanism for guns in which the breech-block upon the block-handle being moved at a uniform speed receives a movement the velocity of which decreases as it approaches the locking position, so that it is pressed with increasing force against the guiding-surfaces, the new mechanism being provided, moreover, with a locking mechanism which prevents an accidental opening of the breech, which often occurs in the mechanisms hitherto used in consequence of the 15 shock caused by the discharge of the gun.

Unlike the breech mechanisms hitherto used, in which the breech-block must be first unlocked by a short turning movement and is 20 then removed by a suitable pulling action, the mechanism forming the subject of the present invention enables the breech-block to be unlocked and withdrawn from the locking position by a single turning movement of 25 the handle.

In the accompanying drawings, Figure 1 shows an elevation of the breech mechanism with the block in closed position. Fig. 2 is a plan view of the same, while Fig. 3 represents 30 the mechanism in its open position. Figs. 4, 5, and 6 are detail views of the handle portion.

The closing-block *b* is arranged at right angles to the barrel in the breech *a*. The 35 face of the block *b* more remote from the barrel is wedge-shaped and slides in a corresponding wedge-shaped recess or opening *d* in the breech, Figs. 2 and 3. Near to the head of the block *b* there is provided a 40 recess or slot *e*, which is arranged at right angles to the axis of the block and receives a lug *f*, which by means of a pin or bolt is pivoted to an arm *h* of the operating-handle *g*. The handle *g* is pivoted at *i* to an extension 45 of the breech-wall and is so formed, as illustrated in Figs. 4 and 6, that a space is left 50 between the handle and the arm *h* thereof,

the width of which space corresponds to the thickness of the extension-wall of the breech.

In the breech-opening there is provided a 55 recess *j*, into which the lug *f* enters when the block reaches its locking position.

The operation of the mechanism is as follows: For locking the breech the handle *g* is turned from the position shown in Fig. 3 60 in the direction of the arrow toward the barrel, whereupon the lug *f* will slide in the groove *e* and force the block *b* inward into the breech. When the block reaches its locking position, the sliding lug *f*, which by that 65 time has reached the end of the groove *e*, will pass into the recess *j*, so that the wedge-block is automatically locked in closed position. It is of great importance in such mechanism to press the wedge-block with great 70 force against the charge in its locking position. According to the present invention an increasing pressure upon the block is exerted, owing to the movement of the handle *g* being transmitted through the angle-arm 75 *h*, forming, with the handle *g*, a three-armed lever the arms of which are arranged in such a manner that the path of arc described by the slide-block *f* is at all times vertical to the path or arc of the end of the lever *g*. 80 When the handle *g* is moved with a uniform speed, the velocity of the movement of the block into the breech gradually decreases toward the end and the pressure exerted by the wedge-block against the charge and the 85 breech-wall increases correspondingly. This will be easily seen from Fig. 3, in which the extent of travel of the handle *g* between the points *y*' and *y*''', divided into ten equal parts, represents the corresponding extent of travel 90 *x*' to *x*''' of the block. The lever *g* *h* is so arranged or constructed that its pivot lies with the slide-block *f* in a line parallel or almost parallel to the axis of the block when the latter is in its locking position, and the pressure of the block against the charge and the 95 breech-wall will increase in proportion with the decrease in speed of the forward movement of the wedge. Upon the handle *g* being turned back the slide-block *f* is first 100 drawn out of engagement with the recess *j*, whereupon the block is brought with increasing velocity into its open position.

Having now particularly described and as-

certained the nature of my said invention and in what manner the same is to be performed, I declare that what I claim is—

- 5 1. In a gun, the combination of a gun-breech and a breech-block therein, said breech-block being provided with a groove, a sliding block in said groove, a lever pivoted to the gun-breech, and an arm on said lever in engagement with said sliding block.
- 10 2. In a gun, the combination of a gun-breech having a wedge-shaped recess therein, a wedge-shaped breech-block adapted to fit said wedge-shaped recess in the gun-breech, said breech-block being provided with a groove, a sliding block in said groove, a lever pivoted to the gun-breech, an arm on said
- 15

lever in engagement with said sliding block, and a handle on said lever.

- 20 3. In a gun, the combination of a gun-breech, a breech-block adapted to move transversely in said gun-breech, said breech-block being provided with a groove, a sliding block in said groove, a lever pivoted to the gun-breech, and an arm on said lever in engagement with said sliding block.

25 In testimony whereof I have hereunto set my hand in presence of two subscribing witnesses.

GUSTAV EHRHARDT.
